UNITED STATES PATENT OFFICE

BARTLEY H. KOLLMAN, OF INDIANAPOLIS, INDIANA

DESIGN FOR A SIGN

Application filed June 6, 1932. Serial No. 43,991. Term of patent 14 years.

To all whom it may concern:

Be it known that I, BARTLEY H. KOLLMAN, a citizen of the United States, residing at Indianapolis, in the county of Marion and State of Indiana, have invented a new, original, and ornamental Design for a Sign, of which the following is a specification, reference being had to the accompanying drawing, forming part thereof.

The figure is a perspective view showing one side of a sign, showing my new design, which is the same and duplicated on the reverse side thereof.

I claim:

The ornamental design for a sign, as shown and described.

BARTLEY H. KOLLMAN.
